UNITED STATES PATENT OFFICE.

EDWIN R. McCALL, OF LOCKPORT, NEW YORK.

PLOW ATTACHMENT.

SPECIFICATION forming part of Letters Patent No. 228,916, dated June 15, 1880.

Application filed April 12, 1880. (No model.)

To all whom it may concern:

Be it known that I, EDWIN R. McCALL, of Lockport, in the county of Niagara and State of New York, have invented certain new and useful Improvements in Plow Attachments; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates to an improvement in plow attachments; and it consists in the clevis A, the standard B, and draft-hook C, and in the combination and arrangement of the parts, as hereinafter more fully described.

In the drawings, Figure 1 is a side elevation of my invention. Fig. 2 is a plan view thereof. Fig. 3 is a sectional elevation of the draft-hook.

A represents a clevis, having the longitudinal plates *a a*, which are fitted upon the upper and lower side of the plow-beam *a'*, and the vertical shoulder *f*, which unites the said plates and the disks *b b*, which latter are provided with the vertical apertures *a''*, shaped for reception of the standard.

B marks a partly-hollow vertical standard, having its bearings on the axle *b'* of the wheel D, it being solid and flattened from the top of the periphery of the wheel to the axle thereof. It is also provided with the horizontal teeth *d* and horizontal orifices *e*. It is adapted, with its teeth, to be inserted into the vertical slots in the disks *b b*, and when therein inserted and turned round a half-revolution the respective disks of the clevis A are retained in position

by the teeth *d*, as shown, and jolting of the beam thus prevented.

The draft - hook C is provided with the shoulder or recess *h*, which is adapted to receive one of the teeth *d*, and in connection with its orifices *e c* for reception of the bolt *d'*, the standard B and wheel D being thus rendered readily and quickly adjustable to the line of the draft, as the hook C is thus rigidly secured to the standard. This construction also causes the direction of the plow-beam to be quickly adjusted to the line of the draft - hook, whereby the intended purpose is accomplished economically and with facility.

The standard B, although constructed tubular, and being partly flattened at the lower part thereof, as aforesaid, a grooved or fluted standard may be employed with equal facility and with results alike beneficial.

What I claim is—

1. The combination of the standard B, having teeth *d*, adjustable in connection with disks *b b*, and hooks C, with recess *h* for reception of teeth *d*, substantially as shown, and for the purpose described.

2. The combination of the standard B, with orifices *e*, teeth *d*, disks *b b*, with apertures *a''*, shaped for reception of standard, and hook C, with shoulder for reception of a standard-tooth, substantially as shown, and for the purpose described.

In testimony that I claim the foregoing as my own I affix my signature in presence of two witnesses.

EDWIN R. McCALL.
